UNITED STATES PATENT OFFICE.

NORMAN LIPSKY, OF NEW YORK, N. Y., ASSIGNOR TO ARTCRAFT METAL STAMPING CORPORATION, OF BROOKLYN, NEW YORK, A CORPORATION OF NEW YORK.

DESIGN FOR THE DECORATION OF A LIGHTING-FIXTURE OR SIMILAR ARTICLE.

56,757.

Specification for Design.

Patented Dec. 14, 1920.

Application filed April 19, 1920. Serial No. 375,170. Term of patent 7 years.

To all whom it may concern:

Be it known that I, NORMAN LIPSKY, a native of Russia, having filed my first papers for citizenship in the United States of America and about to make application for my second papers, and a resident of the city of New York, in the borough of Manhattan, county and State of New York, have invented a certain new, original, and ornamental Design for the Decoration of Lighting-Fixtures or Similar Articles, of which the following is the specification, reference being had to the accompanying drawing, forming a part thereof.

Figure 1 is a plan view showing my new design.

Fig. 2 is a side elevation of a lighting fixture embodying my new design.

I claim:

The ornamental design for the decoration of a lighting fixture or similar article, as shown.

Signed at New York city, in the borough of Manhattan, county and State of New York, this 15th day of April, 1920.

NORMAN LIPSKY.
